HOLDER FOR A PAPER PAD

Anthony Zacharia, 5935 Colfax Ave., North Hollywood,
Calif. 91601

Filed Oct. 16, 1967, Ser. No. 8,997

Term of patent 14 years

U.S. Cl. D74—1
Int. Cl. D19—99; D6—99

FIGURE 1 is a front elevational view of the holder for a paper pad showing my new design;

FIGURE 2 is a side elevational view of the holder;

FIGURE 3 is a rear elevational view of the holder;

FIGURE 4 is a longitudinal cross-sectional view of the holder;

FIGURE 5 is a front perspective view of the holder; and FIGURE 6 is a rear perspective view thereof.

The essential features of my design reside in the portions shown in solid lines; conventional mounting slots being shown in broken lines in FIGS. 3 and 6.

I claim:

The ornamental design for a holder for a paper pad, substantially as shown and described.
